UNITED STATES PATENT OFFICE.

WILLIAM M. BRUCE, JR., OF SPRINGFIELD, OHIO.

TELEGRAPHY.

Application filed April 24, 1920. Serial No. 376,353.

To all whom it may concern:

Be it known that I, WILLIAM M. BRUCE, Jr., a citizen of the United States, residing at Springfield, in the county of Clark and 5 State of Ohio, have invented certain new and useful Improvements in Telegraphy, of which the following is a specification.

My invention relates to improvements in operating printing devices over submarine 10 cables or conductors of high capacity.

The primary object of my invention is to provide methods and apparatus by which a plurality of messages may be sent in the same direction over a single conductor at the same 15 time.

In carrying out this invention I employ for the most part standard apparatus now already in use in connection with new and improved circuits and apparatus and original 20 methods of operating them.

A primary feature of my invention is the utilization of the usual current impulses of opposite polarity in connection with means for changing the character of certain 25 of these impulses, (preferably in respect to their voltage) and further to provide for a suppression or neutralization of all impulses when certain conditions arise in the operation 30 of a plurality of transmitters at the same time and by the utilization of these different conditions produced by the simultaneous 35 operation of said transmitters (preferably automatic) to operate separate translating devices at the receiving end of the conductor which will respond to either one 40 or more of the plurality of transmitters sending separate messages at the same time and to cause the said messages to be simultaneously printed on separate printing devices.

Since as above indicated my invention is capable of use with present standard apparatus, I have illustrated the method of carrying out my invention in diagrammatic form in which—

Fig. 1 represents circuits and apparatus at the sending end of the conductor and

Fig. 2 represents the circuits and apparatus at the receiving end.

Referring first to Fig. 1, α represents a 50 submarine cable having the usual artificial line α^1 with the condensers α^2 , α^3 for duplex operation, the usual cable battery B with transmitting relays b and b^1 which relays are supplied with armatures b^2 and b^3 normally resting on back contacts b^4 and b^5 and adapted, when the relays are operated, to

engage forward contacts b^6 and b^7 . The cable is connected to the armature b^2 by wire 1 and the armature b^3 is connected to earth at g . The back contacts b^4 and b^5 of the respective armatures are connected to the positive side of battery B by wire 2 and branch wire 3, a resistance r being inserted between the wire 2 and the negative side of the battery which resistance is normally shunted by the wires 2 and 4 and the armature c^1 of a relay c which normally engages a back contact c^2 . The forward contacts b^6 and b^7 of the transmitting relays b and b^1 are connected to the positive side of the battery by wire 5 and branch wire 5^a so that when either of the relays b or b^1 is operated (with the relay c in its normal position and the shunt around the resistance r thus closed) positive or negative impulses will be transmitted to the cable 75 in the usual way. That is to say, if the relay b should be operated its armature b^2 will move to the forward contact b^6 and a circuit will be established from earth g to armature b^3 , back contact b^5 , wire 2, contact c^2 , armature c^1 and wire 4 to negative side of the battery, thence by branch wire 5^a and wire 5, contact b^6 , armature b^2 and wire 1 to the conductor α . If relay b^1 should be operated its armature b^3 will move to the forward 80 contact b^7 and a circuit will be established from earth at g through armature b^3 , forward contact b^7 , wire 5, branch wire 5^a to the opposite side of the battery, thence by wire 4, armature c^1 , contact c^2 , wire 2, branch wire 90 3, back contact b^4 , armature b^2 and by wire 1 to conductor α . In other words, these positive and negative impulses would be supplied to the cable by connecting the negative side of the battery to earth and the positive side 95 to cable and the positive side to earth and the negative side to cable in the usual way upon the operation of the relays b and b^1 .

It will be seen now that if the relay c is operated when either a positive or negative impulse is transmitted by the operation of one of these transmitting relays b or b^1 , the shunt around the resistance r will be open and the impulse sent by the operation of either of the transmitting relays b or b^1 will 100 have its potential reduced to the extent of the resistance r (which will thus be brought into the circuit) in either case.

For operating the printing devices I preferably employ a five unit code and each 110 automatic sending device will, therefore, be provided with five circuit closers, and these

circuit closers will be permanently connected to the usual constantly rotating distributor which will be in any of the well known methods synchronized with similar distributing devices at the receiving end.

In providing for sending two separate messages in one direction I employ two of these transmitting devices or rather two sets of circuit closers preferably permanently connected to the revolving parts of the distributor and I so arrange the circuits from these circuit closers that those constituting one set or one transmitter send only positive impulses and the other set send only negative impulses.

In Fig. 1 of the drawings I have shown two such transmitters, each composed of one set of these circuit closers. The one adapted to said positive impulses, for instance, I will call transmitter A and the other adapted to send negative impulses I will call transmitter A¹, it being understood that each of these different transmitters will be operated by a separate punched tape in the usual way but each tape carrying the code characters for a separate and distinct message.

As the particular method for operating these transmitters and sending the impulses to the cable through a distributor D will be the same as now generally employed, a brief description only of this operation will be necessary. It may be stated, however, preliminarily that inasmuch as five code bars are used on the receiving printers, each operated by a relay in response to an impulse of a polarity for that particular printer, impulses of an opposite polarity from that utilized by the particular printer are suppressed.

40   Where printers are employed in which relays are used adapted to be operated by impulses of opposite polarity, that is, positive and negative for each printer, the arrangement will be somewhat different and this 45 particular part of my invention will be made the subject-matter of a separate application.

For the present it is only necessary to keep in mind that when a message is being sent by transmitter A positive impulses only (representing the particular character sent) are transmitted and the negative impulses are suppressed. When operating transmitter A' the reverse is the case, the negative impulses only are sent and the positive impulses are suppressed.

With the above explanation it will be seen upon reference to Fig. 1 of the drawings that the contacts 1, 2, 3, 4, and 5 of the distributor D are connected to the circuit closers b , b^1 , b^2 , b^3 , b^4 and b^5 of transmitter A by wires 11, 12, 13, 14 and 15 and the circuit closers e^1 , e^2 , e^3 , e^4 , e^5 of transmitter A¹ are connected to the same contacts by branch wires 11^a, 12^a, 13^a, 14^a and 15^a and

inasmuch as these circuit closers in both transmitters move synchronously with the contacting arm f of the distributor, if one of these circuits closers should be operated it would send an impulse to that particular 70

contact upon which the arm f is resting at the time. It will be noticed that these circuit closers d^1, d^2, d^3 , etc. of the transmitter A and those e^1, e^2, e^3 , etc., of the transmitter A^1 normally rest upon back contacts d^6, d^7 . 75

A^4 normally rest upon back contacts a^1 , a^2 , a^3 , a^4 , a^5 , a^6 , a^7 , a^8 , a^9 and a^{10} and that these contacts d^6 , d^7 , d^8 , etc., are connected by wires 6, 7, 8, 9 and 10 to one side of relays h^1 , h^2 , h^3 , h^4 and h^5 and that contacts e^6 , e^7 , e^8 , etc., are connected by wires 6^a , 7^a , 8^a , 9^a 80

and 10^a by a common battery wire 16 to one side of a battery B¹, the other side of which is connected by a common battery wire 17 and corresponding branch wires to the other side of the relays h¹, h², h³, etc. The result of this arrangement is that whenever the

circuit closers of a corresponding number or position in both the transmitter A and A' are in their normal or back position the circuit for the relays h^1 , h^2 and h^3 , etc., are 90

closed, but in case either one of the said circuit closers has been operated the circuit for that particular relay $h^1, h^2, \dots$, will be open and the armature h^6, h^7, h^8, h^9 and h^{10} of that particular relay will be released and 95

fall back opening the circuit as will be more fully described hereinafter. The forward contacts d^{11} , d^{12} , d^{13} , d^{14} and d^{15} of the transmitter A are connected by the common wire 18 to one side of relay $\bar{b}$, the other side of

18 to one side of relay δ the other side of which is connected by wire 19 to battery B^2 , the other side of which battery is connected by wire 20 to the revolving arm f of the distributor. The forward contacts $e^{11}, e^{12}, e^{13}, e^{14}$ and e^{15} of transmitter A^1 are similarly 104

e^{14} and e^{15} of transmitter A² are similarly connected by wire 21 to one side of relay b^1 the other side of which is connected by wire 22 to battery B². It should be noted that relays b and b^1 have two sets of windings for

lays 5 and 6. Now, however, the purpose hereinafter more fully explained. One set only is included in the circuit thus described. From the description thus far it will be noted that if in the opera- 116

tion of the distributor D one of the circuit closers d^1 , d^2 , d^3 , etc., of the transmitter A is operated a circuit will be established through that particular circuit closer, for instance, through wire 12, contact 2 of

instance d^2 , through wire 12, contact 2 of the distributor to the arm f (which will be resting on contact 2 at that time) and through wire 20, battery B^2 , and wire 10 to one coil of the relay b and through wire 18

one coil of the relay b and through wire b to the contact d^1 upon which the circuit closer arm d^2 is resting at the time; the movement of the circuit closer d^2 from its back contact will have broken the circuit for the relay b^2 permitting its armature b^7 to

the relay h^2 , permitting its armature h^1 to drop back breaking the circuit through this armature. A similar result would be obtained if either or all of these circuit closers 12

should be successively operated against their forward contact and away from their back contacts.

If a circuit closer in transmitter A¹ should be operated as the distributor D is revolving, circuit closer e³ for instance, a circuit would be established from said circuit closing arm by wires 13^a and 13 to the third contact of distributor D on which the distributor arm

10 f is resting at the time, thence through wire 20, battery B², wire 22 and one coil of relay b¹, wire 21 to the forward contact e¹³. As these respective circuit closers can only be operated when the traveling arm f of the

15 distributor is resting on the particular contact element which is connected with that particular circuit closer an impulse can be sent from that particular closer only, as the others will be open.

20 It will be seen, therefore, that when one or more circuit closers of one transmitter only is operated a number of positive or negative impulses corresponding to the number of circuit closers operated will be

25 sent into the cable through the operation of the transmitting relays b or b¹ depending upon which one of the transmitters is operated and this particular impulse positive or negative will be sent to cable at the

30 time that the distributor arm is upon the particular contact element corresponding to that particular circuit closer and consequently at the time when a synchronously moving distributor at the other end of the cable or

35 conductor is upon the corresponding contact as will be more fully set forth hereinafter.

Now there remains two other conditions to be described as each have an important function to perform in the complete opera-

40 tion of this method or system of operating multiplex printers. One of these conditions is where one circuit closer in each of the transmitters is operated. Inasmuch as the circuit closers in each of these transmitters

45 will operate transmitting relay b or transmitting relay b¹ it follows that when a circuit closer in each transmitter is operated at the same time both of the relays b and b¹ will be operated with the result that the

50 cable will be grounded through line 1, armature d², contact b⁶, wire 5, contact b⁷, armature b⁸ to ground and nothing will be transmitted to the cable or, in other words, it will be in a zero condition.

55 This is important because this zero condition is an important element in the operation of the receiving devices.

The other condition to consider is where no circuit closer is operated in either of the transmitters A or A¹.

It may be stated primarily that in this condition provision is made for sending reversals into the cable for each unit of the distributor, that is, as the distributor arm

65 passes over its respective contacts there will

be sent into the cable successive impulses of positive and negative current, or (in other words, an impulse of different polarity from the next preceding one), so long as neither one of the circuit closers in either of the transmitters is operated but these impulses will pass through the resistance r and consequently each impulse will be of a lower potential than the impulses which are sent to the cable by the operation of either of the circuit closers in either one or the other of the transmitters A or A¹. This is accomplished as follows: The armatures h⁶, h⁷, etc., of relays h¹, h², etc., are connected by a common wire 23 to one side of a battery B³ which in turn is connected by wire 24 and branch wires 25 and 26 which lead respectively to one side of the second winding of the relays b and b¹ and from the opposite end of these respective windings the circuits pass through wires 27 and 28 to contacts i¹ and i² of a relay i, the armature i³ of which is connected by wire 29 to one side of the relay c and thence by wires 30, 26 and 20 to the distributor arm f. Relay i is a pole changing relay and is connected in a circuit from the cable or conductor a by wires 1, 31, 32, 33, 34 and armature k¹ of a relay k which armature is connected by a wire 35 to a condenser 36, the other side of which is connected to wire 32. Relay k is grounded at g¹ on one side and on the other side is connected through branch wire 37 and wire 31 to cable wire 1 and hence receives an impulse when either one of the transmitting relays b or b¹ is operated. The armature k¹ engages contacts k² and k³, one of which is connected to wire 34 and the other to ground at g²; the result being that at each impulse sent to cable the relays i and k will be operated; the relay k from an impulse transmitted to the cable and relay i from the condenser discharge so that armature i³ will rest first upon one contact i¹ and then upon the other i² and in either case the relay c will be operated and the shunt through the wires 2 and 4 around the resistance r will be open.

Assuming now that none of the circuit closers of either transmitter is operated when the contacting arm f of the distributor D passes upon its first contact element (1), a circuit will be traced as follows:—distributor arm f, contact 1, wires 11 and 11^a, armature h⁶, wire 23, battery B³, wires 24 and 25, second winding of relay b, wire 27, contact i¹, armature i³, wire 29, relay c,

wires 30, 26 and 20 back to contact arm f, thus completing a circuit through battery B³ and operating the transmitting relay b. 125

This will send a positive impulse into the cable and will cause the relay i to shift its armature to contact i². When the arm f moves to the next contact member 2 a circuit may be traced from said contact 2 130

115

120

125

- through wires 12, 12^a, armature *h*¹, line 23, battery B³, wires 24 and 26 (number 2) winding of relay *b*¹, wire 28, contact *i*², armature *i*³, wire 29, relay *c*, wires 30, 26 and 5 20 to contact arm *f* thus completing the circuit through battery B³ and the second winding of transmitting relay *b*¹, causing said relay to operate sending a negative impulse to the cable; this being repeated 10 as the arm *f* contacts successively the different contacting elements of the distributor, sending for each unit in the rotation of the distributor an impulse of opposite polarity to the cable. Inasmuch, however, as relay 15 *c* will be operated whenever either transmitter relay *b* or *b*¹ is operated through its second winding the shunt around the resistance *r* will be open at *c*² and these successive reverse impulses to cable will pass 20 through the resistance *r* and consequently at a lower potential.
- This explains the different character and the different characteristics of the impulses which will be transmitted for the different 25 code combinations from the sending end whether sent from one or both of the respective transmitters A and A¹.
- It remains to describe the circuits and apparatus at the receiving end to determine how these impulses and their characteristics are employed to operate the code bars of the printers at that end.
- Referring now to Fig. 2 I will proceed to describe the operation of the receiving 30 apparatus and circuits by which the printing devices are operated. There is connected to the cable or conductor *a* and the artificial line *a*¹ a main receiving relay *m* which is preferably of the suspended coil type and 35 provided with the standard circuits for such receiving instruments in cable practice. I preferably use this receiving relay *m* in the nature of a galvanometer having a mirror on the suspended coil adapted to reflect a 40 beam of light from a lamp L passing through suitable lenses to a resistance device consisting of several elements which elements are of such a nature that their conductivity will be varied under the influence of light, such for instance as 45 selenium. I preferably employ three of these elements *s*¹, *s*² and *s*³, although the element *s*³ is divided into two sections, one section being adjacent to each one of the elements *s*¹ and *s*². Each one of these elements is connected in a circuit with battery to the 50 primary of a transformer; these transformers being shown at T¹, T², T³, a battery to supply these circuits being indicated by B⁴. 55 Battery wire 38 to one side of the battery B⁴ with its branches 39 and 40 connect one side of battery B⁴ to one side of the primary *p* of each of the transformers T¹, T², T³. Wires 41, 42 and 43 connect the opposite 60 65 end of the transformer primaries to the re-

spective sensitive elements *s*¹, *s*² and *s*³, and a common battery wire 44, with branches, connect the opposite sides of these elements to the other side of the battery B⁴.

Now if the relay *m* should receive a positive impulse of normal strength such as is impressed on the cable when the resistance *r* of the sending apparatus is shunted, the beam of light will be moved to the left across the left half of the element *s*³ and rest on the element *s*¹. The result will be to change the resistance of these elements causing a disturbance in the primary of the transformers T¹ and T³ and induce a current in the secondary windings of these transformers. If a negative impulse of the same strength should be received on relay *m* a beam of light will be moved to the right across the other half of the sensitive element *s*³ and onto the sensitive element *s*². This will cause a change in the primary of the transformers T² and T³ setting up by induction current in the secondaries of these transformers.

Now, if a current of either polarity but of less potential such as would come into the cable from the sending end with the resistance *r* in the circuit this beam of light would move only far enough to rest on one section or the other of the sensitive element *s*³, hence the transformers T¹ and T² would not be affected and the transformer T³ only have a current induced in its secondary.

Connected in circuit with the secondaries of the respective transformers T¹, T² and T³ are relays R¹, R², R³ preferably of the suspended coil type and whose coils are respectively provided with tongues *t*¹, *t*², *t*³, these respective tongues in connection with forward contacts *t*⁴, *t*⁵, *t*⁶ form circuit closers 100 for local circuits which include local relays *n*¹, *n*² and *n*³ and batteries B⁵, B⁶ and B⁷ so that whenever either one of the relays R¹, R² and R³ is operated one of the relays *n*¹, *n*², *n*³ will be correspondingly operated.

For the printing mechanism I employ two distributors D¹ and D² the distributing arms of which will be preferably located on the same shaft and synchronized with the distributor D at the sending station in any well known manner. For the code bars of the respective printing devices of which in this case there will be two, I employ the usual code bar relays which are indicated here as CB¹, CB², CB³, CB⁴ and CB⁵ for one printing device and CR¹, CR², CR³, CR⁴ and CR⁵ for the other printing device.

It will be noted that the distributing arms *f*¹ and *f*² of the respective distributors D¹ and D² normally electrically connected by wires 45 and 46 through batteries B⁸ and B⁹, this circuit passing through the respective armatures *n*⁴, *n*⁵, *n*⁶ of the relays *n*¹, *n*² and *n*³ and through wires 47, 48 and 49 and 50. The respective code bar relays CB¹,

CB², CB³, CB⁴ and CB⁵ of what may be called No. 1 printer are connected to the respective contact elements of distributor D¹ by wires 51, 52, 53, 54 and 55. The respective code bar relays CR¹, CR², CR³, CR⁴ and CR⁵ of what may be termed the No. 2 printer are connected to the contact elements of distributor D² by wires 51^a, 52^a, 53^a, 54^a and 55^a. A common return wire 56 connects the opposite ends of each of these relays to the forward contacts n⁷ and n⁸ of the relays n¹ and n².

If in this situation a positive impulse of normal strength is received by the cable relay m, a beam of light will be deflected to the left across one section of the sensitive element s³ and onto the sensitive element s¹ which through the transformers T³ and T¹ will operate the relays R³ and R¹. This will in turn close the circuits for relays n³ and n¹ at contacts t³, t⁶ and t¹, t⁴, causing relays n³ and n¹ to operate. As the armature n⁶ of relay n³ moves away from its back contact the circuit between the batteries B⁸ and B⁹ will be broken. As the armature n⁴ moves away from its back contact by the operation of relay n¹, the circuit will be broken at this point also and will remain broken so long as the relay n¹ is energized even though the relay n³ should be deenergized. As the armature n⁴ moves to the forward contact n⁷ a circuit is established from battery B⁸ through wire 47, armature n⁴, contact n⁷, common wire 56 to one side of each of the code bar relays of No. 1 printer and if at this particular moment the contacting arm f¹ is resting for instance on No. 2 contact that particular code bar relay will be operated. If it should rest on any other contact the corresponding relay will be operated. If the light should be held over by a succession of impulses as many code bar relays will be operated as there are impulses and hence the code bars of the printing devices will be properly set for printing.

If a negative impulse or set of impulses should be received on the cable relay m the beam of light would move to the right crossing the right hand section of the sensitive element s³ and onto the sensitive element s² which would successively operate relays R³ and R². Relay R³ would operate relay n⁸ which would break the circuit as before between the batteries B⁸ and B⁹ at n⁶ and the operation of relay R² would close the circuit for relay n² at contact t⁵ causing relay n² to operate, bringing its armature n⁵ into engagement with forward contact n⁸ and breaking the circuit between the batteries at the back contact of this relay. A circuit would thus be established from battery B⁹ through wire 46 to the contacting arm f² of the distributor D² and through this arm and through the contact it may be resting upon

to the particular code bar relay of No. 2 printer which is connected to that particular contact thence back through common wire 56, contact n⁸, armature n⁵, wire 50 to battery B⁹. 70

I have thus described the means for operating either code bar of either printer synchronously with the operation of either circuit closer of either transmitter at the sending end as these positive or negative impulses can only be sent into the cable by the transmitter A or the transmitter A¹ at a time when the contacting arm f of sending distributor D is resting upon the corresponding contact with which the distributing arm of the receiving distributor D¹ or D² is engaging at the receiving end. 75

I will next describe the operation when an impulse of lower potential is impressed upon the cable which it will be remembered will occur when no circuit closer of either transmitter is operated and which results in sending to cable successive impulses of opposite polarity but of lower potential. This will result in the operation of the cable relay m to a lesser degree and cause the beam of light to move successively to the different sections of the sensitive elements s³ only and inasmuch as neither the sensitive elements s¹ or s² will be affected, relay R³ only will be operated through its transformer T³. The operation of relay R³ in turn will energize the relay n³ thus breaking the circuit between the batteries B⁸ and B⁹ so that as the distributing arms f¹ and f² pass over the distributor contacts neither of them will find battery and hence none of the code bars in either of the printers will be operated. 90 95

It remains to describe what will take place when a circuit closer in each of the transmitters is operated at the same time. It will be remembered that when this takes place the cable remains in a zero condition, no impulses of either sign being impressed thereon. In that case the cable relay m is not affected. The beam of light remains in the zero position between the respective sections of the sensitive element s³ and neither of the relays R¹, R², R³ are operated and the 100

circuits and apparatus remain in the normal position as illustrated in Fig. 2 of the drawings. If this should happen when both of the distributor arms f¹ and f³ were on the third contact for example of each of the 110 distributors (which would be true in case the third circuit closer of each of the transmitters A and A¹ were operated) these contacting arms would find battery on each of these contacts No. 3 in the respective distributors and I would have a circuit from contacting arm f¹ through wire 45, battery B⁸, wire 47, armature n⁴, wire 48, armature n⁶, wire 49, armature n⁵, wire 50, battery B⁹, wire 46, contacting arm f² through the third 115 120 125 130

contact on distributor B^2 , wire 53*, code bar relay CR^3 , code bar relay CB^3 , wire 53 to the third contact element in distributor D^1 upon which arm f^1 is resting, completing the circuit. Both code bar relays CB^3 and CR^3 would thus be operated and the proper code bars for both of the printers be set to perform the printing operation.

It will be thus be seen that so long as the 10 cable is in zero position, which in this case can only happen when the corresponding circuit closers of each of two transmitters are operated at the same time, the corresponding code bar relays of both of the 15 printers will be operated by the synchronous operation of the distributors D^1 and D^2 . The moment that the circuit closer of one transmitter is operated and the corresponding circuit closer of the other transmitter is 20 not operated then a positive or negative impulse will be sent, depending upon whether it was the A transmitter or the A^1 transmitter that was operated.

Inasmuch as it is now common practice to 25 operate printers of this character and to provide means for word spacing and for performing the printing operation and also for properly synchronizing the distributors, these operations and the devices for accomplishing them are not described. The particular installation to which my improved 30 method of sending signals is shown applied is the five unit code now in use by the Western Union Telegraph Company and others. 35 The same method of sending and receiving signals, however, can readily be used in connection with any of the other well known printing systems by simple modifications of the local circuits to suit their particular 40 conditions.

By the use of the two transmitters and the two printers employing the five unit distributor, thirty-two different combinations can be secured for each of these transmitters 45 and printers which are ample to provide for all the characters used in printing telegraphy with upper and lower case, spacing key shift, etc.

Having thus described my invention, I 50 claim:

1. In a system for sending and receiving a plurality of messages over a conductor, means for sending current impulses of different polarity for one message and of the opposite polarity for a different message, and causing a zero condition where impulses of opposite polarity appear simultaneously in different messages, and separate means at the receiving end operated 55 by the positive and negative impulses and by the zero condition of the cable, as set forth.

2. The method of operating simultaneously a plurality of printing devices so 60 as to receive separate messages in the same

direction over a single conductor at the same time which consists in using for transmitting each message positive and negative impulses with a plurality of variations of current for certain operations and a zero condition where impulses of opposite polarity appear simultaneously in different messages as set forth.

3. The method of simultaneously operating 75 two printing devices so as to send and receive two messages in the same direction over a single conductor at the same time which consists in employing two transmitting devices, one adapted to transmit positive impulses and the other negative impulses and producing a zero condition on the cable when corresponding units of the respective transmitters are operated at the same time and causing the operation of one of said printing devices from impulses of one polarity and the operation of the other printing device from impulses of opposite polarity and the operation of similar units of both printing devices from the zero cable 80 conditions as described.

4. In a system of printing telegraphy, two transmitting devices having the same code units connected to a single distributor, two printing devices each with a distributor synchronized with the sending distributor, one of said transmitting devices being adapted to send positive impulses which shall be received on one of the receiving distributors and the other transmitting negative impulses which will be received on the other distributor and to cause simultaneous operation of corresponding parts in both printers when the corresponding unit of both transmitters are operated, substantially as described.

5. The method of telegraphing over a submarine cable which consists in utilizing current impulses of one sign for operating a translating device and impulses of the opposite sign for operating a different translating device and a zero condition of the cable for simultaneously operating both translating devices.

6. The method of transmitting a plurality 115 of messages over a single conductor which consists in using current impulses of one polarity for one message and current impulses of the opposite polarity for the other message and creating a zero cable condition when two impulses of opposite polarity are impressed on the cable and utilizing these different current impulses and zero condition for operating different translating devices.

7. In a telegraph system for transmitting 125 a plurality of messages over a single conductor, means for sending positive impulses for signals in one message and negative impulses for signals in the other message, and creating a zero condition when impulses 130

of the same polarity occur, and means for utilizing the positive and negative impulses for causing a beam of light to move to one light affected element in response to the impulses of one polarity and to a different light affected element by impulses of the opposite polarity and translating devices from each of said light affected elements to be operated in response to the impulses of either polarity and a separate translating device adapted to be operated when neither of said elements are affected or when the light is in zero position.

8. In a system of printing telegraphy, a plurality of printing devices each having a plurality of operating units, a light reflecting mechanism operated in different directions and to different degrees in the same direction by different signal impulses, a plurality of light-affected-resistance-elements in the line of travel of said reflected light, one for each degree of light movement, said resistance elements being severally connected to and adapted to operate different translating devices, said different translating devices being arranged to operate the different units of the several printers in response to different current impulses as set forth.

9. In a telegraphing system as described, for receiving and translating telegraph impulses of different impulses for different messages and which embodies a plurality of sets of light affected resistance elements, and means for illuminating said resistance elements in response to the impulses of different polarity and a translating device connected to and operated by the change in resistance of each of said elements as the same is illuminated, said translating device being arranged to operate recording devices to record different signals or signal elements when the light is moved in either direction and a separate translating device adapted to operate automatically when neither of said resistance elements are illuminated, as specified.

10. The combination with a plurality of sending devices connected to a single distributor at one end of a cable, means for causing current impulses of opposite polar-

ity and of different potentials of the same polarity under different conditions of operation of said transmitters, receiving and translating devices at the other end of the cable embodying a light reflecting galvanometer moving in opposite directions and to varying degrees in the same direction in response to said transmitters, a plurality of sets of light-affected-resistance-elements and a translating device connected to each element and a recording device operated by each translating device whereby the different recording devices will be operated by the different light-affected elements when the light is moved to different positions in either direction as set forth.

11. In a system of printing telegraphy, a plurality of transmitting devices at one end of a conductor and a plurality of printers at the other end, means connected with said transmitters for causing impulses of opposite polarity and of different potential of the same polarity to be impressed upon the conductor and means at the receiving end to produce a certain condition of the respective printing devices by impulses of different polarity and a different condition by impulses of different potential of the same polarity and a third condition by a zero condition of the cable and utilizing these various conditions for simultaneously operating a plurality of printers as set forth.

12. The method of receiving a variable potential telegraphic current consisting of positive, negative and zero impulses, whereby two simultaneous telegraphic messages are recorded over a single conductor by the employment of three or more selenium or other light-affected resistance elements so arranged that a beam of light responding to the variations of either positive or negative and the zero impulses operate telegraph printing mechanism to record two separate simultaneous messages.

In testimony whereof, I have hereunto set my hand this 22nd day of April, 1920.

WILLIAM M. BRUCE, JR.

Witness:

CHAS. I. WELCH.
